CLAIM

I claim the ornamental design for a vehicle air dam, as shown and described.

DESCRIPTION

FIG. 1 is a perspective view of a vehicle air dam showing my new design;

FIG. 2 is a front view of the vehicle air dam;

FIG. 3 is a top view of the vehicle air dam;

FIG. 4 is a bottom view of the vehicle air dam; and, FIG. 5 is a left side view of the vehicle air dam, with the right side view being a mirror image.
